UNITED STATES PATENT OFFICE

147,486

DESIGN FOR A COOKING RANGE

William Bauer, Mansfield, Ohio, assignor to The Tappan Stove Company, Mansfield, Ohio, a corporation of Ohio

Application May 22, 1946, Serial No. 129,984

Term of patent 14 years

(Cl. D81—4)

To all whom it may concern:

Be it known that I, William Bauer, a citizen of the United States and a resident of Mansfield, in the county of Richland and State of Ohio, have invented a new, original, and ornamental Design for a Cooking Range, of which the following is a specification, reference being had to the accompanying drawing, forming a part thereof, wherein

Fig. 1 is a perspective view of a cooking range showing my new design;

Fig. 2 is a sectional view taken on the line 2—2 of Fig. 1; and

Fig. 3 is a fragmentary view in side elevation showing the top portion of the stove.

The dominant features of the design reside in the portions shown in full lines.

I claim:

The ornamental design for a cooking range, as shown and described.

WM. BAUER.
